JOSEPH S. DOX

By Watson C. Coleman

Attorney

UNITED STATES PATENT OFFICE.

JOSEPH S. COX, OF BERTHOLD, NORTH DAKOTA.

BUNDLE-CARRIER.

1,246,239.

Specification of Letters Patent. Patented Nov. 13, 1917.

Application filed May 7, 1917. Serial No. 137,007.

To all whom it may concern:

Be it known that I, JOSEPH S. Cox, citizen of the United States, residing at Berthold, in the county of Ward and State of North Dakota, have invented certain new and useful Improvements in Bundle-Carriers, of which the following is a specification, reference being had to the accompanying drawings.

10 This invention relates to certain improvements in bundle carriers, and has relation more particularly to a device of this general character especially adapted for use in connection with sheaves of grain; and it is an 15 object of the invention to provide a novel and improved device of this general character of a materially large capacity and which is capable of readily and conveniently dumping or discharging a load when the requirements of practice may necessitate.

It is also an object of the invention to provide a novel and improved device of this general character adapted to coact with a binder, and wherein the carrier is connected 25 directly to the binder.

The invention consists in the details of construction and in the combination and arrangement of the several parts of my improved bundle carrier whereby certain important advantages are attained and the device is rendered simpler, less expensive and otherwise more convenient and advantageous for use, all as will be hereinafter more fully set forth.

35 The novel features of the invention will hereinafter be definitely claimed.

In order that my invention may be the better understood, I will now proceed to describe the same with reference to the accompanying drawings; wherein

40 Figure 1 is a view in side elevation of a bundle carrier constructed in accordance with an embodiment of my invention, a second or dumping position thereof being indicated by dotted lines;

45 Fig. 2 is a view in perspective of the rock shaft for supporting and operating the body of my improved carrier as herein embodied; and

50 Fig. 3 is a somewhat diagrammatic view

in top plan, with a part in section, of my improved carrier and a coacting portion of a binder, the body of the carrier and the operating means therefor, including the supporting shaft, being omitted.

55

As disclosed in the accompanying drawings; B is a diagrammatic representation of a portion of a binder to which is suitably affixed a socket S, having coacting therewith a ball 1, carried by the outer extremities of the converging arms 2. The opposite ends of the arms 2 are hingedly connected as at 3, with a side beam 5 of the frame F. The frame F is supported by the wheels 4, positioned intermediate the side beams and 60 mounted upon the axle 6 carried by the frame F and disposed transversely thereof. The operative connection between the binder B and the frame F is afforded by the arms 2, which serve to maintain the frame F in 65 substantially a constant position relative to the binder B, so that the sheaves or bundles as delivered from the binder may be readily deposited in my improved carrier by an operator standing upon the platform P supported by the arms 2. The forward end of 70 the frame F is provided with an extension E, with which is operatively engaged a draft rigging D, as it is my purpose to employ an extra draft animal coacting directly 75 with my improved carrier.

As disclosed in Fig. 3 of the drawings, it will be noted that the draft rigging D is positioned substantially in alinement with a draft rigging D' of the binder proper, and 80 which is indicated in fragment in Fig. 3.

The side beams 5 of the frame F are each provided with a substantially V shape side member 7, having its apex upwardly disposed and arranged substantially in vertical 85 alinement with the axle 6. The apices of the members 7 are provided with the upstanding bearings 8, with which the rock shaft 9 is operatively engaged. Mounted for rocking movement at substantially its longitudinal 90 center is the body or basket 10, and said body or basket 10 is of materially large capacity. In practice I have found it best to have the body or basket 10 of such capacity as to receive about forty bundles or sheaves. It is 95 100

to be understood that the bundles or sheaves as delivered from the binder B are manually stacked or placed within the body or basket 10.

- 5 The body or basket 10 is of such a length as to have the rear end portion thereof extend beyond the rear end of the frame F. Interposed between the rear portion of each of the beams 5 of the frame F and the rear 10 portion of the corresponding side of the basket or body 10, is a toggle lever T, the sections 11 of which are of substantially the same length. Operatively engaged with the pivot 12 connecting with the sections 11 15 is a lever or elongated link 14, also operatively engaged with an upstanding rock arm 15, carried by an end portion of the shaft 9. The rock arms 15 are in parallelism, as are also the levers or links 14, whereby it will 20 be perceived that upon rearward movement of the rock arms 15 and the levers or links 14, the sections 11 of the toggle levers T will be folded, and result in the body or basket 10 assuming a dumping position as indicated 25 by dotted lines in Fig. 1. The rocking movement of the body or basket 10 under the influence of the links 14 is limited by the contact of the body or basket 10 with the rear members and the side members 7 of the 30 frame F.

Upon forward movement being imparted to the levers or links 14, the body or basket 10 will be swung upwardly to the position shown in full lines in Fig. 1, or in a position to receive the sheaves or bundles as 35 delivered from the binder B.

- Carried by a side of the body or basket 10 is a segmental rack 16, concentric to the shaft 9. The adjacent rock arm 15 is continued upwardly to afford an operating handle 17, and said handle 17 is provided with a conventional latch mechanism 18, coacting with the rack 16, whereby it will be perceived that the body or basket 10 may be 40 effectively locked in a raised position. I also find it of advantage to provide the outer end portion of the extension E with an extra wheel W, or its equivalent, for a purpose which is believed to be self-evident. 45 The body or basket 10 is provided with a tail gate G, hingedly or pivotally connected at its lower marginal portion, as indicated at 19, for swinging movement in a vertical direction. Each side of the body or basket 50 10 above the pivotal or hinged connection 19 is provided with a guide pulley 20 or the like, with which coacts the flexible member 21, having its outer end portion suitably secured to the gate G, while the opposite end 55 portion of said flexible member 21 is operatively engaged with a rod 22, operatively connected with the pivot member 12 of the adjacent toggle lever T. By this arrangement it will be perceived that when the rear

portion of the body or carriage 10 is lowered, the gate G will be free to swing downwardly in order to permit the discharge of the load carried by the body or basket 10. It will also be self-evident that as the rear portion of the body or basket 10 is elevated, the gate G will be caused automatically to assume a closed position and be maintained effectively in such closed position.

In view of the foregoing it is thought to be self-evident that my improved device is of materially large capacity, which allows the operator to clear the greater portion of his field immediately the crop is cut, thus permitting plowing to be started at once. While it is true that an extra man will be required in the crew and also an extra draft animal, a material saving of time in harvesting is effected which materially offsets the additional cost of operation. With the use of my improved carrier it is possible to leave the field in such condition as to permit immediate plowing of substantially eighty per cent. of the field. My improved carrier also materially saves time in shocking and threshing.

From the foregoing description, it is thought to be obvious that a bundle carrier constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I also find it of advantage to provide the forward portions of the side members 7 with the upstanding posts or brace members 23, upon which the forward end portion of the body or basket 10 rests when the same is at the limit of its upward movement. The posts or brace members 23 serve to relieve the toggle levers T from excessive strain which would otherwise be imposed thereon by the load.

I claim:

A bundle carrier including a portable frame, a body pivotally supported by the frame, a toggle connection between the frame and body, means coacting with the toggle for raising and lowering the body, a vertically swinging tail gate having its lower marginal portion hingedly engaged with the body, a flexible connection between the gate and the toggle connection for automatically closing the gate upon movement of the body.

in one direction, and a guide member carried by the body above the hinged connection between the gate and body and with which the flexible connection co-acts, said gate assuming an open position by gravity upon movement of the body in the opposite direction.

In testimony whereof I hereunto affix my signature in the presence of two witnesses.

JOSEPH S. COX.
